Primary Examiner — John A Voytek(74) *Attorney, Agent, or Firm* — Robert N. Lipszik; June E. Rickey(57) **CLAIM**

The ornamental Design for a tire, as shown and described.

DESCRIPTION

FIG. 1 is a perspective view of a tire showing our new design, it being understood that the pattern repeats uniformly throughout the circumference of the tread; FIG. 2 is a right side elevational view thereof; the left side elevational view being identical thereto; and, FIG. 3 is a front elevational view thereof.
